JAMES H. DOBBS, OF ALLENTOWN, PENNSYLVANIA, ASSIGNOR TO L. F. GRAMMES & SONS, INC., OF ALLENTOWN, PENNSYLVANIA, A CORPORATION OF MARYLAND.

CLINCHING NAIL.

Application filed February 10, 1925. Serial No. 8,102.

This invention relates to clinching nails and it has more particular reference to nails for use in the shoe making, repairing and leather industries. At present, clinching 5 nails employed in the arts referred to may be generally classified as of two varieties: namely:—Iron cut nails fabricated from bar stock with a sharp point that lends itself to quick application to leather; and nails made 10 from wire which clinch when driven into leather and naturally hold securely. The former type of nail, as a result of its sharp point, penetrates leather by slight pressure thereby enabling it to be quickly driven, but 15 it has a tendency to break-off easily due to its inherent lack of pliability. Another disadvantage is that iron cut nails do not clinch readily and hence are lacking in security. Wire nails, on the other hand being more 20 pliable do not break-off easily, but they possess the disadvantage of not being sufficiently penetrative for quick driving with an attendant loss of time and labor, as they must be "set"; or given an initial start, before 25 being driven.

My invention has for its primary object to provide a clinching nail embodying all the advantages of the above referred to types of nails with none of the stated 30 disadvantages.

Other objects and advantages inhering to this invention will be later on referred to, and it may be tersely defined as consisting essentially in fabricating a relatively shorter shanked nail from wire with a comparatively longer sword-section point, which clinches with a distinctive curl when driven thereby ensuring a much firmer hold.

The accompanying sheet of drawings 40 typify an advantageous embodiment of this invention such as is particularly serviceable in the shoe making and repairing industries, while the appended claims succinctly recite the subject-matter believed to be novel.

45 In the drawings:—

Fig. I is an enlarged view of a clinching nail embodying the characteristic features of this invention.

Fig. II is a view at right angles to the 50 preceding illustration; and,

Fig. III is a transverse section taken as indicated by the arrows III—III in Fig. II.

Referring more in detail to the drawings, and bearing in mind the above recited objects, my novel type of clinching nail, com-

prehensively designated by the numeral 5, is made from metal wire of suitable gauge cut into predetermined lengths. Each length is fashioned in any of the well known ways to provide a head 6, shank 7, and relatively longer—or major—penetrative portion 8. This latter portion 8 is what constitutes the fundamental of my invention, hence particular attention is directed to the distinctive contour and cross-section thereof. As shown, it will be observed, the penetrative portion 8 is of "sword" cross-section to provide diametrically opposed cutting edges 9, 9, and relatively stiffer or blunt edges 10, 10, at right angles thereto; all of 60 said edges gradually merging from the shank 7 towards the nail tip or point 11. It is also noteworthy that the nail faces 12 intervening the aforesaid edges 9, 10, are longitudinally concaved to assist the penetrative action.

From the foregoing it will be clearly understood that the relatively long sword-section penetrative portion 8, of my improved nail, lends itself to easy application to leather by a mere pressure on the head 6, whereupon it can be quickly driven without danger of springing back, while its penetrative action is clean cut. Nails 5, of the section set forth herein will be found to clinch with 80 a distinctive curl when driven into leather upon a last or other non-penetrative surface with a consequent better hold. Again my improved nails 5, having a shorter shank 7, with a correspondingly longer penetrative 85 portion 8, than any others at present in vogue for analogous use will drive into leather more easily, because fully one half thereof acts as a cutter, while being hammered into said leather. Still further I find that my improved nails clinch with less of a hump or bulge than others, heretofore in use, as a natural result of the thinner penetrative section.

Obviously, detail changes relative to the 90 proportions of the respective parts of my novel clinching nail may be effected, without departing from the fundamental features involved, accordingly the right is hereby reserved to make such variations as are 95 fairly encompassed by the appended claims.

Having thus described my invention, I claim:—

1. A wire clinching nail having the major portion of its length of sword-blade cross 100

section to afford longitudinal blunt and cutting edges respectively lying in planes at right angles to each other, said cutting and blunt edges gradually merging to the nail point.

2. A wire clinching nail having the major portion of its shank fashioned to sword-blade cross section thereby affording opposed longitudinal cutting edges and opposed blunt edges with intervening concaved faces, said cutting edges and blunt edges gradually merging toward the point of the nail.

3. A clinching nail fabricated from a length of wire to provide a headed shank ¹⁵ and a penetrative portion of relatively greater extent, said penetrative portion being grooved to sword-blade cross section thereby providing opposed longitudinal cutting edges and opposed blunt edges each ²⁰ having a decreasing merge from the shank into the nail tip.

In testimony whereof, I have hereunto signed my name at Allentown, Pennsylvania, this 5th day of February, 1925.

JAMES H. DOBBS.
